UNITED STATES PATENT OFFICE.

JAMES E. EMERSON AND THOMAS MIDGLEY, OF BEAVER FALLS,
PENNSYLVANIA.

GRIPPING-DIE FOR CORRUGATING AND BARBING WIRE NAILS.

SPECIFICATION forming part of Letters Patent No. 372,845, dated November 8, 1887.

Application filed August 15, 1887. Serial No. 247,000. (No model.)

To all whom it may concern:

Be it known that we, JAMES E. EMERSON and THOMAS MIDGLEY, citizens of the United States, residing at Beaver Falls, in the county 5 of Beaver and State of Pennsylvania, have invented certain new and useful Improvements in Dies for Corrugating and Barbing Wire Nails; and we do hereby declare the following to be a full, clear, and exact description of the 10 invention, such as will enable others skilled in the art to which it appertains to make and use the same.

Our invention relates to dies for forming and barbing or nicking wire nails, and will be 15 hereinafter described, and particularly pointed out in the claims.

In the accompanying drawings, which form a part of this specification, Figure 1 is a plan view of one-half of a die. Fig. 2 is a longitudinal transverse section of one-half of a die. Fig. 3 is a side view of a finished nail. Fig. 4 is an end view of the die. Figs. 5 and 6 are diagrammatic views of the dies. Figs. 7, 8, and 9 are enlarged detail views of insertible 25 cutters for the die.

Reference being had to the drawings and the letters marked thereon, A A represent the two halves or sections of the die for forming the nail of our manufacture, and each half or 30 section is provided with a semi-cylindrical groove, a, which extends throughout its entire length. The adjacent or meeting surfaces of the two sections A A are corrugated throughout a portion of their length, leaving the semi-cylindrical groove intact at both ends of the 35 die, as shown in Figs. 1 and 2, for the purpose of corrugating a portion of the body of the nail made in the die.

The barbs or niches b in the nail B are 40 cut by teeth c, formed on the ends of dovetailed cutters d, which are inserted in the die transversely from each side in dovetailed grooves e, and are held in position by side plates, f g, which may be attached to the sections A A 45 by dovetail projections h engaging with corresponding grooves i, or they may be attached with rivets or screws.

C in Fig. 5 represents the heading-die or hammer for upsetting the projecting end k of the stock (shown in Fig. 6) and forming the

head of the nail in the recess in one end of the die for forming the body of the nail.

The dies thus constructed grip the stock, corrugate the nail, and hold it against longitudinal displacement while the teeth c are 55 forced or driven into the sides of the projection l of the nail and form the barbs or niches b, and roughen the surface of that portion of the nail and cause it to hold more firmly in the wood into which it is driven. By thus 60 firmly gripping and corrugating a portion of the body of a nail in the die, the nail is absolutely held against longitudinal displacement, and the heads of all nails made in the die are 65 of uniform thickness.

The dies of our improved construction may be applied to the usual form of machines employed for manufacturing wire nails, and the insertible cutters may be applied to other forms of dies for making other articles without departing from the spirit of our invention. 70

Instead of having two sets of cutters to form the barbs or niches on both sides of the projections l of the nail, a cutter may be employed which will form them on the apex of 75 said projections, or one side only.

In another application filed herewith, Serial No. 246,999, we have claimed the nail.

Having thus fully described our invention, what we claim is—

1. A die for the manufacture of nails, having a longitudinal groove in the adjacent faces of its sections, a portion of said groove having plain smooth surfaces and the remaining portion being corrugated and provided with 85 projections or teeth to form barbs or niches on the corrugated portion of a nail, substantially as described.

2. A die for the manufacture of nails, having a longitudinal groove in the adjacent faces 90 of its sections, a portion at each end of said groove being in the same plane and having smooth surfaces, and an intermediate corrugated portion having projections or teeth to form barbs or niches on the corrugated portion of the nail, substantially as described.

3. A die for the manufacture of nails, made in sections having a portion of their adjacent surfaces corrugated and provided with a longitudinal groove, a portion of which is corrugated 100.

gated, and projections or teeth to barb or niche the surface of part of the corrugated portion of a nail, substantially as described.

4. A die made in sections and provided with 5 insertible cutters and corrugated adjacent surfaces, in combination with a hammer or heading-die, substantially as described.

In testimony whereof we affix our signatures in presence of two witnesses.

JAMES E. EMERSON.
THOMAS MIDGLEY.
